UNITED STATES PATENT OFFICE.

ARLEN C. TAYLOR, OF CLAY CENTER, KANSAS.

VACUUM WATER-CIRCULATOR.

1,349,638.

Specification of Letters Patent. Patented Aug. 17, 1920.

Application filed January 17, 1920. Serial No. 352,034.

To all whom it may concern:

Be it known that I, ARLEN C. TAYLOR, a citizen of the United States, residing at Clay Center, in the county of Clay, State 5 of Kansas, have invented certain new and useful Improvements in Vacuum Water-Circulators; and I do hereby declare the following to be a full, clear, and exact description of the invention, such as will enable others skilled in the art to which it 10 appertains to make and use the same.

This invention relates to new and useful improvements in cooling systems and particularly to cooling systems for explosive 15 engines.

The principal object of the invention is to provide a novel and improved apparatus by means of which a more perfect and constant circulation of water from the engine jacket, through the radiator, and back 20 to the jacket, can be attained.

Another object is to provide a novel and improved water circulating system which is operative at different speeds in accordance 25 with the speed of the engine.

Another object is to provide a novel and improved system of this character which is automatic in its operation.

A further object is to provide a novel and 30 improved system of this character which delivers moisture to the gas in the intake manifold.

Other objects and advantages will be apparent from the following description when 35 taken in connection with the accompanying drawings.

In the drawings:

Figure 1 is a diagrammatic view of the system.

Fig. 2 is a sectional detail view of the 40 vacuum tank and valve connected thereto.

Fig. 3 is a sectional detail view of the connection to the atmosphere and the valve thereof.

Referring particularly to the accompanying drawings, 10 represents the cylinder block of the engine, which has the water jacket 11. This jacket is connected to the upper portion of the radiator 12 by the pipe 13, and to the lower portion of the radiator by the pipe 14. The radiator is provided with the usual filling tube 15, but engaged on this tube is a supplemental tube 16, on which is engaged the novel cap 55 17, used in connection with the present in-

vention. In one side of the cap supplemental tube is secured one end of a pipe 18 which passes downwardly and rearwardly where it is connected to a depending pipe 19 carried by the bottom of the suction or 60 vacuum tank 20. This tank is preferably mounted on the side of the engine or cylinder block. A pipe 21 leads from this pipe 19 downwardly to discharge condensation to the ground. A ball valve 22 is located 65 in the juncture of the pipes 18 and 19 the same being mounted to seat by virtue of the suction created in the tank. From the upper end of the tank a pipe 23 leads to and is tapped into the side of the vertical leg 70 of the intake manifold 24, a controlling shut-off valve 25 being located in this pipe.

Tapped into the pipe 14, at the point of juncture with the water jacket, is an L-shaped pipe 26, the horizontal portion of 75 which opens into the water in the jacket, while the other end extends above the engine and is turned downwardly, as shown at 27, the latter end being open to the atmosphere, as will be readily understood from 80 an inspection of the drawings.

The operation may be briefly described as follows:

The engine being in motion suction will be created in the intake manifold which will 85 draw vapor from the upper portion of the radiator, through the pipe 18, into the tank 20, and thence into the intake manifold. This is assuming that the valve 25 is open. The suction draws the ball valve 22 to its 90 seat preventing atmospheric air from entering the depending leg 21. The water in the radiator, the pipes 13 and 14, and in the water jacket will thus move in a direction toward the radiator to fill the vacuum caused 95 by the suction through the pipe 18. As this suction continues the atmospheric air will be drawn in through the pipe 26, with the result that the ball valve 28 will be lifted from the seat, thus permitting the atmospheric air to pass through the water and up to the space within the filling tube of the radiator, from whence it is drawn through the pipe 18. The vapor which enters the tank in excess of that used or drawn into the intake manifold, will condense and collect in the bottom of the tank. When the engine stops, the suction created by the manifold ceases, thus relieving the valve 22, which is opened by the water from the tank, said 110

water passing out through the pipe 21 to the ground.

There is thus provided a novel and efficient cooling system wherein the water is forced to circulate through the water jacket and radiator while the engine is running, but when the engine stops the vacuum of the system is immediately filled and the excess moisture in the upper part of the radiator is permitted to easily and quickly drain to the ground.

What is claimed is:

1. In a water circulation system for an explosive engine the combination with a water jacket and radiator and connections therebetween, of a vacuum tank, connections between the tank and the intake manifold of an engine, connections between the tank and the radiator above the water level therein, and valved connections between the water jacket and the atmosphere.

2. In a water circulation system for explosive engines the combination with a water jacket, radiator, and intake manifold of the engine, of a vacuum tank connected to the manifold and to the radiator above the water level therein, a valved outlet from the tank to the atmosphere for draining condensation from the tank, a cut-off valve between the tank and the manifold, and a

valved inlet from the atmosphere to the water jacket.

3. In a water circulation system for an explosive engine the combination with the water jacket and radiator and the connections therebetween and the intake manifold of the engine, of a tank located between the radiator and the manifold, a conduit connecting the radiator above its water line to the bottom of the tank, a valved extension in the conduit at the point of connection with the tank, the valve of said connection being arranged to open normally to discharge water from the tank and to close under the influence of suction in the tank, a conduit connecting the upper end of the tank and the manifold for creating suction in the tank under the influence of the gases passing through the manifold, and a pipe connecting the water jacket with the atmosphere in which is disposed a valve normally closed by the water in the jacket and arranged to open to permit air to enter upon suction being produced in the system.

In testimony whereof, I affix my signature, in the presence of two witnesses.

ARLEN C. TAYLOR.
